United States Patent Office

Des. 180,512
Patented June 25, 1957

180,512

TOY AIRPLANE

Silas M. Ford, St. Paul, Minn.

Application March 12, 1956, Serial No. 40,553

Term of patent 14 years

(Cl. D34—15)

FIG. 1

FIG. 2

FIG. 3

FIG. 4

Figure 1 is a perspective view of a toy airplane, showing my new design;

Figure 2 is a side elevational view of the same;

Figure 3 is a top plan view of the same; and

Figure 4 is a front elevational view of the same.

I claim:

The ornamental design for a toy airplane, as shown.
